SUPPORT FOR HOLLOW ARTICLES PROVIDING MEANS TO CONTROL THE COOLING OF THE MATERIAL WITHIN THE ARTICLE

Erwin E. Franz, Cranford, N. J., assignor to Western Electric Company, Incorporated, New York, N. Y., a corporation of New York

Original application July 26, 1944, Serial No. 546,708. Divided and this application May 19, 1945, Serial No. 594,611

4 Claims. (Cl. 226—70)

1

This is a division of the applicant's copending application, Serial No. 546,708, filed July 26, 1944, now Patent 2,489,878, and relates to support for hollow articles providing means to control the cooling of the material within the article, more particularly to machines for potting electrical units.

In the manufacture of certain electrical units such as coils of particular types, metallic casings, commonly known as cans, are provided to house the coils or given portions thereof, the casings being filled with an insulating compound. In filling cans or containers of electrical units with a sealing compound which is poured into the container in a molten state and allowed to cool, there exists fissures or other pockets in the material. If the material is allowed to cool normally without any controlling factor, the heat of the material will be expelled through the metal container and the material will therefore begin its solidification adjacent the container, resulting in the presence of the fissures adjacent the core or central portion of the unit in which the members to be sealed are disposed.

An object of the invention is to provide a loading machine which is simple in structure, efficient in operation, and highly practical for hollow articles.

With this and other objects in view, the invention comprises a support for a hollow article, means to fill the article with a molten material, and means to control the cooling of the material.

Other objects and advantages will be apparent from the following detailed description when considered in conjunction with the accompanying drawings, wherein

Fig. 1 is a horizontal sectional view of the machine;

Fig. 2 is a fragmentary vertical sectional view taken substantially along the line 2—2 of Fig. 1;

Fig. 3 is an enlarged fragmentary vertical sectional view of one of the unit supports;

Fig. 4 is a fragmentary elevational view of the machine; and

Fig. 5 is an enlarged fragmentary sectional view taken along the line 5—5 of Fig. 2.

Referring now to the drawings, attention is first directed to Fig. 1 which illustrates a base 20 supported by suitable legs 21 and centrally apertured to receive a supporting bracket 22. A reduced end 23 of a stationary shaft 24 is supported in the central aperture of the bracket 22, the latter being fixedly mounted in the aperture of the base 20 by means of screws 25. An annular apertured plate 28, disposed concentric with

with the shaft 24, rests upon the bracket 22 and is fixed thereto as at 29. Annular grooves 30 and 31 are formed in the bracket 22 in registration with sets of apertures 32 and 33 in the annular plate 28. A similar annular member 34, with like apertures therein for communication with their respective apertures 30 and 33, is also disposed concentric with the shaft 24 and is fixed to a hub 36. The hub 36 includes bearings 37 and is rotatable on the shaft 24. The hub is a part of a turret indicated generally at 38 and having an upper member 39, an intermediate member 40, and a lower member 41. Through the aid of these members compartments 42 and 43 are formed, closed at the outer edges thereof through the aid of an annular member 44. By viewing Fig. 2, it will be noted that sets of passageways 45 and 46 complete communication with their respective sets of apertures in the annular plate 28 and annular member 34.

In the present embodiment the electrical unit includes a molded body 50 supporting a plurality of terminals and having coils or other structures formed thereon, the leads of which are fixed to their respective terminals 51. A metallic can or container 52 is disposed over the upper portions of the body 50 and the inner structure of the unit, an aperture 53 being provided in the upper end of the container. The bodies 50 are hollow for given portions of their lengths to receive supports 54. The supports 54 are identical in structure, there being provided a multiplicity of pairs thereof disposed in circular arrangement as illustrated in Figs. 1 and 2.

Attention is directed to Fig. 3 for the detailed structure of the supports 54. The support illustrated in this figure includes a hollow member 56 of the cross-sectional contour shown, closed at its upper end 57, upon which the body 50 rests, and including a thin-walled upper portion 58 and a larger lower portion, the latter being threaded at 59 and disposed in a threaded aperture 60 of the upper member 39 of the turret. A tubular member 61, supported in a threaded element 62, mounted in a threaded aperture 63 of the intermediate member 40, extends into the hollow member 56 short of the full length thereof and spaced from the inner wall of the member to allow for the passage of a cooling fluid therebetween. The tubular member 61, therefore, communicates with the compartment 42, while the member 56 communicates with the compartment 43.

In potting electrical units, that is, in filling cans or containers thereof with a sealing com-

ound which is poured into the container in a molten state and allowed to cool, there exist fissures or other pockets in the material due to cooling and solidifying thereof. In such materials are allowed to cool normally without any controlling factor, the heat thereof will be expelled through the metal container and the material will, therefore, begin its solidification adjacent the container, resulting in the presence of the fissures adjacent to the core or central portion of the unit in which the members to be sealed are disposed. This would be undesirable as the fissures would leave portions of the vital portions of the unit unprotected against foreign particles and atmospheric conditions. With the knowledge of these facts, the turret 38 is constructed as previously described, so that a cooling medium, such as water, may be circulated therethrough and through each of the supports 54, to cause the cooling of the sealing material toward the center of each unit, other means for retarding the cooling of the material nearer the container, such as by the application of heat to the container, being hereinafter described.

The cooling medium or water may be received from a supply line 65 through a thermostatically controlled valve 66 to the groove 30. The water, when admitted under force to the groove 30, will travel through the companion apertures in the members 28 and 34, through the passageways 45, into the compartment 42, through the tubular member 61 of each of the supports 54, overflowing at the upper ends thereof and passing downwardly, contacting the thin wall of the member 56 within each of the units and escaping through the compartment 43, passageways 46, through the companion apertures in the annular members 34 and 28, through the annular groove 31, and through a suitable outlet 67. A control unit 68, positioned to successively engage the outer supports 54 during their intervals of rest, functions through the connection 69 in controlling the valve 66.

Means is provided to intermittently move the turret 38 about the fixed shaft 24 and to lock it against movement during its intervals of rest. The moving means includes a motor 70 (Fig. 1) which is operatively connected to an input shaft 71 of a speed reducing unit 72 through a belt and pulley connection 73. An output shaft 74 of the unit 72 extends vertically and has a cam element 75 mounted upon the upper end thereof and a cam 76 mounted upon the lower end thereof. The cam element 75 is keyed, as at 78, to a sleeve 79, the latter being fixed to the shaft. The purpose of this connection is to allow the cam element 75 to be moved vertically into and out of operative positions under the control of a cam surface 89 positioned to ride upon a cam roller 81, the latter being supported by a cup-shaped structure 82 fixedly supported by the base 20. A circular arrangement of pins 84 are disposed at spaced positions in alignment with the inner circle of supports 54, to function in cooperation with a cam member 85 for the movement of the turret a given distance, namely the distance between the centers of the pins 84, to advance the supports 54 one station during each cycle of the cam element 75. There is also provided a cam portion 87 positioned to ride under the adjacent pin 84 during each cycle of the cam element 75 to force the latter downwardly should it not move downwardly by gravity under the control of the roller 81.

A cam groove 89 is formed in the periphery of the cam element 85 and of a contour to cause

rocking of a locking lever into engagement with the adjacent pin 84 at the termination of each intermittent movement of the turret. In this manner the turret is locked against rotary movement during the rest period thereof, so as to automatically align the apertures 53 of the containers 52 with the nozzles of the units or valves for feeding the sealing material thereto, as will hereinafter be described.

10 A hood 97, arcuate in general contour, surrounds the supports 54 excepting at the loading position at the front of the machine, indicated at 98 (Fig. 1), where the units, to be filled, are placed upon the supports 54 and those which 15 have been filled and passed through the machine may be removed. The hood 97 has a main compartment 100 and an auxiliary compartment 101 separated by a partition 102 in which a series of apertures 103 (Fig. 1) are disposed in circular 20 arrangement throughout the partition. A heating unit 104, which may be of any desired contour, is positioned adjacent an inlet 105 for the compartment 101, so that air from a blower 106 actuated by an electric motor 107 may be heated 25 while passing into the compartment. The partition with its apertures 103 distributes the heated air throughout the compartment 101 and causes it to pass uniformly into the compartment 100 to heat the containers 52.

30 A receptacle 110 for sealing material 111 is rigidly mounted upon the shaft 24 and has an outlet 112. Suitable means (not shown) may be provided to heat the material 111 in the receptacle 110 to convert it into a liquid so that it will 35 flow freely through the outlet 112 to valves 114 and 115. The valves are disposed in a housing 116 which includes a heating element, indicated generally at 117, which is under the control of a thermostat 118 to maintain the valves and the material at a desired temperature. Outlets or 40 nozzles 120 and 121 are provided for the valves 114 and 115, respectively, and are positioned to register with units during each interval of rest of the turret 38. The valves 114 and 115 have levers 45 123 and 124 fixed to their outer ends, they in turn being pivotally connected to the adjacent ends of actuating rods 125 and 126, respectively. These rods are slidably supported in suitable 50 bearings 127 and carry cam-like fingers 128 and 129. Springs 130, disposed concentric with the rods between one of the bearing members 127 and their fingers 128 and 129 normally urge the rods to the right, to cause movement of the valves into open positions. Solenoids 132 and 133 are 55 provided to release the actuating rods 125 and 126, they functioning in cooperating with the fingers 128 and 129.

The solenoid 132 has a link 135 connecting its spring pressed core 136 to a lever 137, the latter 60 being pivotally supported at 138 and carrying a roller 139 at its outer end, as illustrated in Fig. 1. When the core of the solenoid 132 is in its normal position the roller 139 is in the path of the finger 129 to hold the actuating rod 125 in a position 65 to the left, the roller 139 being removed from the path of the finger upon energization of the solenoid. A similar structure is provided for the solenoid 133, including a link 140 connecting its spring pressed core 141 with a lever 142, the latter being 70 pivotally supported at 143 and carrying a roller 144. The roller 144 is positioned in the path of the finger 128 to hold the finger, together with its actuating rod 126, to the left against the force of its spring 130 until the solenoid 133 is energized. 75 The actuating rods 125 and 126 have collars 145

and 146 at given positions thereon positioned to be engaged by a slide 148, carried by the rods and movable through the actuation of an arm 149, which is connected to the slide through the aid of a pin or screw 150 receivable in an elongate aperture in the end of the arm. The arm 149 is fixedly mounted upon the upper end of a shaft 152 which is supported in suitable bearings and extends downwardly to a position beneath the base 20, where a cam lever 153 is mounted thereon. The cam lever 153 is shown in Fig. 2 and carries a cam roller 155, at its outer end, which is normally held in engagement with the cam 76 so that during each revolution of the cam, the cam lever 153 will be moved clockwise to move the arm 149 (Fig. 1) in the same direction, to move the slide 148 to force either or both of the actuating rods 125 and 126 so that their fingers 128 and 129 will engage their respective rollers 139 and 144. The cam-like surfaces of the fingers cause actuation of their levers 137 and 142 in movement into their set positions. This is, therefore, the setting mechanism for the valves 114 and 115. When the valves are set, passageways 158 communicate with the passageway 112 leading from the receptacle 110, so that a hollow portion 159 (Fig. 5) of each of the valves may be filled with the sealing material. At this time outlet passageways 160 are closed to their nozzles 120 and 121. Ports 161 are provided for each of the valves 114 and 115, they having pairs of ports 162 to communicate with the ports 161 while the valves are in their respective loading and unloading positions, so that air within the valves may escape during the loading of the valves with the sealing material, and permit air to enter the valves during the unloading of the material into the units so that the liquid material which remains heated in the valves will be allowed to flow freely through the nozzles associated therewith. It will be noted that the larger ends of the valves are closed by covers 163 including integral plug portions 164 (Fig. 1) which may be of varied sizes to vary the volume of the sealing material receivable into the hollow portions 159.

It is important that the valves 114 and 115 are operated to allow their contents of sealing material to pass into the containers 52 as the units are successively positioned therebeneath. It is equally important that the valves remain inoperative should the operator, by accident, allow a filled unit to repeat its cycle of movement through the machine. To assure accurate operation of the valves, micro-switches (not shown) respectively disposed in circuits (not shown) for controlling their respective solenoids 132 and 133 are mounted so that their roller carrying arms will be actuated by the units to be filled but will not be actuated by the units repeating their travel through the machine. The roller carrying arms for the switches are indicated at 167 and 168 and are movable to actuate their respective switches. The positioning of the hollow articles or electrical units relative to the switch arms 167 and 168 is under the control of flexible and extensible endless belts 172 and 173 supported by sheaves so that the upper portions of the belts will engage a plurality of the supports 54, while the lower portions thereof are held out of the path of the pins 84 through the aid of idler rollers or sheaves (not shown). It will, therefore, be apparent that when the operator places units to be filled upon the supports 54 at the loading position 98, certain of the terminals 51 of each of the units will rest upon their respective belt 172 or 173, as indicated

at the left (Fig. 2). By resting upon the belt, the upper end of the unit will be in the path of its respective arm 167 or 168 to cause actuation of its switch. However, if the unit is one which has travelled through the machine and has previously been filled with the sealing material, as illustrated by the unit at the right of Fig. 2, this unit, after passing its respective switch arm 168 during its first travel through the machine, has dropped off of its belt 173 so that as it again approaches the belt, it will be in the lower position with the terminals 51 engaging the side wall of the belt and not resting upon the belt as shown. This difference in position of the unit will locate the upper end thereof beneath its switch arm 168 so that at this time the valve 114 will not be actuated as the solenoid 132 will not be energized. This same incident could occur in connection with the outer belt 172 and regardless of the number of units repeating their travel through the machine they will not interfere with the unfilled units.

Considering now the operation of the apparatus, let it be assumed that the machine is empty of units to be filled. The operator, stationed at the loading position 98 (Fig. 1), places the electrical units upon all of the supports 54, that is, both circular rows thereof, as they are brought into the loading position. The units, 30 therefore, originally rest upon their respective belts 172 and 173 and as they reach their respective switch arms 167 and 168, their switches are closed, causing energization of the solenoids 132 and 133. It is immaterial as to when the solenoids are actuated with respect to each other. They may be actuated simultaneously or at different intervals of time, depending upon the positions of the units on the turret.

Assuming that the valves 114 and 115 have 40 been previously filled with the quantities of sealing material these quantities will be deposited in their respective units, during the rest period of the turret, resulting from the energization of the solenoids to actuate their respective levers 45 and release the fingers 128 and 129 so that the springs 130 may actuate the valves, opening the passageways to their nozzles so that their contents may flow into the containers of the units positioned beneath. This operation continues 50 during the intermittent rotation of the turret which is brought about through the continuous operation of the motor 70 to drive its cam element 75 through the unit 72, to raise the element intermittently so that the cam member 85 will 55 be positioned to engage the next successive pin 84 to rotate the turret 38 a given distance, the turret being immediately locked against further rotation.

During the operation of the machine the air 60 from the blower 106, heated by the heating unit 104, is constantly circulated through the hood 97 to heat the containers 52 of the units being filled to control the solidification of the sealing material so that, through the cooling effect of the supports 54 resulting from the cooling medium or water, the sealing material will cool more rapidly adjacent its center than at the outer portions thereof. This will result in a solid body 65 of the sealing material about the coil or unit within the container, the presence of many fissures being located adjacent the container where they will not affect the unit.

Although specific improvements of the invention have been shown and described, it will be understood that they are but illustrative and

that various modifications may be made therein without departing from the scope and spirit of this invention as defined by the appended claims.

What is claimed is:

1. In a machine for loading a casing surrounding a hollow article with an insulating compound to hermetically seal the article in the casing, the machine comprising a hollow support formed to removably fit into the hollow article and thereby support the article with its casing, a supply unit to support a supply of the insulating compound in a molten state, a valve operable to allow a given quantity of the molten insulating compound to flow from the unit into the casing to fill the casing and surround the article therein with the molten compound, and means to circulate a cooling medium, having a temperature lower than the temperature of the atmosphere surrounding the casing, through the hollow support to cool the support and the hollow article and thereby cool the inner portion of the compound adjacent the article in advance of the cooling of the outer portion thereof adjacent the casing.

2. In a machine for loading a casing surrounding a hollow article with an insulating compound to hermetically seal the article in the casing, the machine comprising a hollow support formed to removably fit into the hollow article and thereby support the article with its casing, a supply unit to support a supply of the insulating compound in a molten state, a valve operable to allow a given quantity of the molten insulating compound to flow from the unit into the casing to fill the casing and surround the article therein with the molten compound, means to circulate a cooling medium, having a temperature lower than the temperature of the atmosphere surrounding the casing, through the hollow support to cool the support and the hollow article and thereby cool the inner portion of the compound adjacent the article in advance of the cooling of the outer portion thereof adjacent the casing, and means to direct a heated fluid to the exterior of the casing to retard the cooling of the outer portion of the compound.

3. In a machine for loading a casing surrounding a hollow article with an insulating compound to hermetically seal the article in the casing, the machine comprising a hollow support formed to removably fit into the hollow article and thereby support the article with its casing,

a supply unit to support a supply of the insulating compound in a molten state, a valve operable to allow a given quantity of the molten insulating compound to flow from the unit into the casing to fill the casing and surround the article therein with the molten compound, a tubular member extending into the hollow support and terminating short of the end thereof, and means to force a cooling fluid through the tubular member to the inner end of the hollow support and cause the cooling fluid to travel through the hollow support to cause cooling the inner portion of the compound adjacent the article in advance of the cooling of the outer portion adjacent the casing.

4. In a machine for loading a casing surrounding a hollow article with an insulating compound to hermetically seal the article in the casing, the machine comprising a hollow support formed to removably fit into the hollow article and thereby support the article with its casing, a supply unit to support a supply of the insulating compound in a molten state, a valve operable to allow a given quantity of the molten insulating compound to flow from the unit into the casing to fill the casing and surround the article therein with the molten compound, a tubular member extending into the hollow support and terminating short of the end thereof, means to force a cooling fluid through the tubular member to the inner end of the hollow support and cause the cooling fluid to travel through the hollow support to cause cooling the inner portion of the compound adjacent the article in advance of the cooling of the outer portion thereof adjacent the casing, and means to direct hot air to the exterior of the casing to retard the cooling of the outer portion of the compound.
